AMUSEMENT APPARATUS

Robert E. Kuenstler, Jr., Rte. 3, Box 33X, and Duane W. Tressler, Box 908, Graham Air Base, both of Marianna, Fla.

Filed July 18, 1958, Ser. No. 749,370

3 Claims. (Cl. 273—1)

The present invention relates generally to a game or amusement apparatus and specifically to an interconnected apparatus for employment by two juvenile persons to simulate the drawing and shooting of pistols as in a gun duel.

An object of the present invention is to provide an amusement apparatus which lends itself to competitive play by two juvenile persons simulating the drawing and shooting of pistols as in a gun duel.

Another object of the present invention is to provide an amusement apparatus which enables two or more juvenile persons to competitively test their abilities in drawing of a weapon from a holster, the apparatus employing means by which one gun or pistol is rendered inoperative if drawn from the holster later than the drawing of the other gun from the holster.

A further object of the present invention is to provide an amusement apparatus which is fool-proof in operation, one simple in structure, one economical to manufacture and assemble, and one which is highly effective in action.

These and other objects and advantages of the present invention will be fully apparent from the following description when taken in conjunction with the annexed drawings, in which:

Figure 1 is an isometric view of the apparatus of the present invention, worn by two persons and showing the method of play while employing the apparatus of the present invention;

Figure 2 is an elevational view of one of the holsters with one of the guns installed therein;

Figure 3 is a schematic view of the electrical circuit employed with the apparatus of the present invention, with parts of the gun barrels each in position actuating a switch mechanism of the circuit, the gun barrel parts being shown in dotted lines;

Figure 4 is a fragmentary sectional view of the assembly shown in Figure 2;

Figure 5 is a fragmentary sectional view of Figure 4 showing the trigger locking mechanism in action;

Figure 6 is a view on an enlarged scale, taken on the line 6—6 of Figure 4;

Figure 7 is a view on an enlarged scale, taken on the line 7—7 of Figure 4;

Figure 8 is an isometric view of a portion of the latching mechanism used in the present invention;

Figure 9 is a fragmentary view taken on the line 9—9 of Figure 8 and on an enlarged scale; and

Figure 10 is an enlarged view of a circuit making portion of the present invention.

Referring in greater detail to the drawings in which like numerals indicate like parts throughout the several views, the reference numeral 12 designates a holster having a gun 14 insertable and withdrawable from the holster 12. The gun 14 has a barrel 16, the free end 18 of which engages one end of a lever 20 when the gun 14 is inserted in the holster 12. A second holster 22 is provided and a gun 24 is insertable into and withdrawable from the holster 22. The construction of each gun 14 and 24 is identical and the construction of the holsters 12 and 22 are

2

also identical and will be described with reference to the holster 12 and the gun 14.

A circuit making and breaking device is positioned with in each of the holsters 12 and 22 and constitutes the levers 5 20 having one end engageable by the adjacent end of the gun 14 or gun 24 on its topside, and by the adjacent core of electromagnet 37 on its bottom side. The lever 20 is connected intermediate its ends by means of a pivot pin 26 to the holster 12 for movement about the pin 26 as a horizontal axis. A small coil spring 28 has one end bearing against the underside of the lever 20 adjacent the pin 26 and the other side bearing against the underside of a frame portion 30 within the holster 12. The spring 28 biases the lever 20 to the position in which the contact 32 10 on the other end of the lever 20 remote from the gun barrel 16 of the gun 14 is in contact with the fixed contact 34 dependingly carried from the frame portion 30. Upon removal of the gun barrel 16 from the holster 12 the lever 20 moves from the position shown in full lines 15 in Figure 10 in which it is held in the open circuit position to the dotted line position under the action of the spring 28 to close the contacts 32 and 34 and to complete the circuit of the apparatus. In the schematic view 20 shown in Figure 3 the spring 28 represents the spring 28 and is shown as a coil spring under compression.

An energizable element, embodying electromagnets 36 and 37, is positioned within the holster 12 at two positions; one underneath lever 20, and the other in the wall of holster 12 adjacent the underside of and intermediate 30 the ends of the barrel 16 of the gun 14 when the gun 14 is in place in the holster 12. The function of the electromagnets 37 is to insure that the circuits in the two holsters, 12 and 22, never remain closed simultaneously. Electromagnets 37, when energized, act to hold switch points 32 35 and 34 open in the same manner that the gun barrel 16 acts when inserted into the holsters against the top side of levers 20. This function will be readily seen as the complete operation of the invention is described. As shown in Figure 1, a junction box 38 is provided and is 40 connected by a paired wire conduit 40 to a source of current such as a wall outlet in a residential house circuit. The junction box 38 is connected by other conduits 42 and 44 to the switches in the bottom of each of the holsters 12 and 22 and to the respective electromagnets 36 and 37 in the holsters 12 and 22. This cross-over connection is shown in Figure 3. In place of the connection to the house current, batteries may be substituted or a step-down transformer incorporated in the junction box 38 in order that the current carried by the contacts 32 and 34 45 be limited to voltages which normally are not dangerous per se.

An articulated locking member 46, Figures 4, 8 and 9, is slidable as a unit within the barrel 16 of the gun 14 and has a triangular enlarged portion 48 on one end thereof constituting a combined cam and hook. The portion 48 50 has a cam face 50 and a hook face 52, as shown most clearly in Figure 8.

The locking member 46 is articulated intermediate its length and the rearward portion 54 is slidably supported in apertures provided in partitions 56 and 58 within the 55 gun barrel 16. For the present, the sliding feature of the locking member 46 is to be put aside for explanation later.

The forward portion 60 of the locking member 46 is 60 biased by a wire spring 62 (Figure 9) which extends on each side of the pivot pin 64 connecting the rearward portion 54 to the forward portion 60 so that the forward portion 60 tends to stay in the aligned end to end position shown in Figure 8. The pivot pin 64 permits swinging movement of the forward portion 60 from the full line 65 position (Figure 4) to the dotted line position in which the enlarged portion 48 is in contact with the core 66 of

the electromagnet 36. The core 66 has an abutment 68 against which the hook face 52 of the portion 48 of the member 46 engages when the coil of the electromagnet 36 is energized and the forward portion 60 of the locking member 46 is swung toward and into engagement with the core of the electromagnet 36. The forward portion 60 of the locking member 46 is of magnetically attractive material and is responsive to energization of the electromagnet 36 to engage the latter and to lock the barrel 16 against withdrawal from the holster 12 when the hook face 52 engages the abutment 68.

A pin 70 is insertable through an opening 72 (Figure 4) in the underside of the gun 14, through an aperture 74 in the rearward portion 54 of the locking member 46 and into an aligned opening 76 in the adjacent portion of the gun barrel 16. When the pin 70 is in position in the registering openings 72 and 76 and traversing the aperture 74 in the locking bar 46, the latter is held against sliding movement within the gun barrel 16.

In operation, the guns 14 and 24 are positioned in their respective holsters 12 and 22 with the free ends 18 and 18' of the barrels 16 and 16' bearing against the adjacent ends of the levers 20 and 20' and holding the associated movable switch contacts 32 and 32' out of engagement with the fixed contacts 34 and 34'. Upon withdrawing of one gun from its holster the gun in the other holster is immobilized and cannot be withdrawn from its holster. This is accomplished in the following manner. Withdrawal of the gun 14 from the holster 12 permits the lever 20 to tilt under urging of the spring 28, engaging the contact 32 with the contact 34 and completing the circuit beginning with one of the power lines 40, extending through wire 39, wire 41, wire 43, wire 45, electromagnet 37', wire 47, electromagnet 36', wire 49, and ending with the other of the wires 40, as shown in Figure 3. This effects the energization of the electromagnets 36' and 37' with the energization of the electromagnet 36' pulling the portion 60 of the lock member of the gun 24 to the position in which the hook face 52 engages the abutment 68 and prevents withdrawal of the gun 24 from the holster 22. Simultaneously, the electromagnet 37' is energized and effects a holding open of the contacts 32 and 34 in case there is any play of movement between the hook face 52 and the abutment 68. The reverse action occurs if the gun 24 is withdrawn from the holster 22. In the latter instance, the gun 14 is held against movement out of the holster 12 by action of the electromagnets 36 which are energized by the current flowing through the circuit which includes wire 49, wire 41', wire 43', wire 45', electromagnet 37, and wires 39 and 47'. Simultaneously, the electromagnet 37 is energized to hold open the contacts 32' and 34' in case there is any play of movement between the hook face 52 of the gun 14 and the adjacent abutment 68.

Referring now to the sliding movement of the locking member 46 which is permitted upon the removal of the pin 70 from the openings 72 and 76 and the aperture 74 provided in the locking member 46, an added feature of the present invention will be described.

Referring to Figures 4 and 5, the gun 14 will be seen to include a trigger 78 and a hammer 80 mounted within the gun 14 for snap action movement in which caps are exploded, such construction and movement being common in cap pistols and for which no invention is claimed. The mechanism for feeding the caps to the hammer 80 is not shown for reasons of simplification.

The trigger 78 is provided with a shoulder 82 against which one end of a lever 84 is under the tension of a coil spring 86 when the locking member 46 has been pulled to the position shown in Figure 5 in which the enlarged portion 48 is adjacent the open end of the barrel 16. Another spring 88 having one or two coils wound about the pivotal connection of the lever 84 to the gun 14, normally pulls the lever 84 to the full line position shown in Figure 4 when the locking member 46 is not drawn to the forward end or discharge end of the barrel 16.

The enlarged portion 48 of the locking member 46 is provided on the side opposite the camming face 50 with a notch 90 which receives a shoulder 92 provided on the inner wall of the barrel 16 inwardly of the discharge end of the latter. The barrel 16 is provided with a slot 94 through which the camming face or cam face partially projects.

When the pin 70 is withdrawn from the aligned openings 72 and 76 and the aperture 74 in the gun barrel 16 and the locking member 46, respectively, upon energization of the associated electromagnet 36, the locking member 46 is drawn toward the electromagnet 36. The gun 14 is no longer locked within the holster 12 and upon withdrawal of the gun 14 from the holster 12, the cam face 50 on the locking member 46 partially projects through the slot 94 with the hook face 52 engaged on the abutment 68 in the holster 12. As the gun 14 is withdrawn, the engagement of the hook face 52 on the abutment 68 causes the locking member 46 to be drawn forwardly of the barrel 16 applying tension to the spring 86 which has one end connected to the rearward end of the locking member 46 and its other end connected to the lever 84 intermediate the ends of the latter. The forward end, Figure 5, of slot 94, acting against cam face 50 as the gun is drawn from the holster 12 causes the forward portion 60 to return to its aligned end to end position with respect to the rearward portion 54 and this effects the engagement of the shoulder 92 in the notch 90, holding the spring 86 under tension and shifting the lever 84 to the position in which its free end is engaged on the shoulder 82 of the trigger 78, restraining firing movement of the trigger 78.

Thus, it will be seen that two actions are provided by the apparatus of the present invention, namely, restraint of one gun from its holster if the other gun is pulled first; and secondly, restraint of the firing movement of the second gun to be pulled from its holster although permitting firing of the first gun from its holster.

Conventional means such as a three-way plug 96 is used to connect the wires within the conduits 42 and 44 with an appropriately constructed socket 98 on the end of the conduits 42 and 44 remote from the junction box 38. The plug 96 is connected by internal wires to the respective sides of the switch embodied by the contacts 32 and 34, the contact 32 having a common ground with the one end of the coil of the electromagnets 36 and 37, which has its other end connected to one of the other wires within the respective conduit 42 and 44, all of conventional construction.

It will be seen, therefore, that the apparatus of the present invention will afford amusement and interest to juveniles and other persons and will enable them to practice withdrawing a gun from a holster and competitively display the dexterity of such persons.

The free end of the enlarged portion 48 projects outwardly of the barrel 16 when the locking member 46 has been moved to the forward position. After one play, finger pressure on the end of the portion 48 will disengage the shoulder 92 from the notch 90 and permit the spring 62 to retract the member 46 to the original position for repeated play.

What is claimed is:

1. Amusement apparatus comprising at least two holsters each adapted to be worn by a person, a circuit closing means normally in closed position in each of said holsters, a gun insertable into and withdrawable from each of said holsters, said guns upon being inserted in the respective holsters shifting said circuit closing means to open position and upon being withdrawn from the respective holsters permitting shifting of said circuit closing means to the normal closed positions, an energizable lock element carried by each of said holsters, means electrically connecting the element on one of said holsters to the circuit closing means on the other of said holsters and the element on the other of said holsters to the circuit closing means on said one of said holsters,

means electrically connecting said circuit closing means to a source of electric current, and a locking member carried by each gun and movable into and out of engagement with the adjacent energizable element, the locking member of the gun when the gun is inserted in one of said holsters being actuated into engagement with the adjacent energizable element responsive to the withdrawal of the inserted gun from the other of said holsters.

2. Amusement apparatus comprising at least two holsters each adapted to be worn by a person, a switch including a fixed contact and a movable contact positioned within each of said holsters adjacent the bottom thereof, the movable contact of each switch being normally in contacting engagement with the fixed contact, a gun including a discharge barrel positioned within each of said holsters so that the free end of said barrel engages the adjacent movable contact and shifts the latter by gravity out of contacting engagement with the adjacent fixed contact, an energizable lock element carried by each of said holsters, means electrically connecting the element on one of said holsters to the switch on the other of said holsters and the element on the other of said holsters to the switch on said one of said holsters,

means electrically connecting said means to a source of electric current, and a locking member positioned within the barrel of each of said guns and connected to said barrel for movement into and out of engagement with the adjacent energizable element, the locking member in the barrel of the gun when inserted in one of said holsters being actuated into engagement with the adjacent energizable element responsive to shifting of the movable contact into contacting engagement with the fixed contact of the switch in the other of said holsters upon withdrawal of the inserted gun from the other of said holsters.

3. The amusement apparatus according to claim 2, wherein said energizable element embodies an electromagnet, and said locking member includes a magnetizable portion.
